UNITED STATES PATENT OFFICE.

WILLIS S. KELSEY, OF MERIDEN, CONNECTICUT, ASSIGNOR OF ONE-HALF
TO HENRY L. MOREHOUSE.

FASTENING MEANS FOR PARQUET FLOORS, PANELING, OR THE LIKE.

SPECIFICATION forming part of Letters Patent No. 748,746, dated January 5, 1904.

Application filed April 10, 1903. Serial No. 151,997. (No model.)

To all whom it may concern:

Be it known that I, WILLIS S. KELSEY, a citizen of the United States of America, residing at Meriden, in the county of New Haven 5 and State of Connecticut, have invented certain new and useful Improvements in Parquetry for Floors, Paneling, &c., of which the following is a specification.

The invention has to do with the finishing 10 of wall, ceiling, or floor surfaces by the application of blocks or panels, and more particularly it has to do with the means employed for securing these blocks or panels in place.

Broadly speaking, it comprehends the use 15 of plates, preferably metallic, each plate engaging two or more blocks which are grooved about their edges for this purpose and means for securing the plates to the floor or other foundation, the entire device when the surface 20 is finished being concealed.

The invention is illustrated as applied to the laying of parquet-flooring.

Figure 1 is a general plan view showing the manner of use of the invention. Fig. 2 is a view similar to Fig. 1, but showing four blocks 25 in position. Fig. 3 is a detail plan view of a single block, with parts broken away to show construction. Fig. 4 is an edge view of the same. Fig. 5 is a view of a bolster.

Referring to the drawings, the edges of the blocks *a* are grooved, as at *b*. Metallic plates *c d*, having arms *m n*, the arms *m* being slightly less in width than the depth of the groove and the arms *n* being in width about 35 twice the depth of the grooves, are provided which engage these grooves, as shown, said plates being screwed to the floor. Recesses for the screws are made by cutting away the block below the groove, as indicated at *e*.

The plates *c d* are made in different shapes 40 to meet the conditions of their use. The plate *c*, being used when four blocks are brought together in the field of the floor, has four arms and the plate *d*, being used to se-

ure adjacent blocks along the edge of a room 45 or against the base-board, having three arms, two of which, *m*, are slightly less in width than the depth of the groove, and the other one, *n*, is wide enough to lie in the grooves in 50 the adjacent blocks when they are brought together.

In laying a parquet-floor the first block laid is preferably in the corner of the room, as at 100. The plates *d* are then positioned, as shown in Fig. 1 at 101 102. The next 55 blocks are then positioned so that the extending arms on the plates *c d* just enter the grooves in said blocks sufficiently to support the plate. The positions of the blocks at this time are shown at 110 112 115 in full 60 lines, Fig. 1. With the blocks in the positions here described the plates are fastened to the floor, as by the screws *g*, which are driven sufficiently to cause the plate to bind the blocks to the floor. The blocks 110 112 65 115 are now driven together, sliding on the plates to their proper positions, as shown in Fig. 2. The recesses *e*, formed along the edges of the blocks, are necessary to permit of the blocks being driven to place without 70 interfering with the fastening-screws. Continuing in this manner the whole floor is laid, each plate binding two or more blocks being secured to the floor by one, two, or three screws, as desired. It results from the use 75 of such a fastening device that when the floor is completed the fastening-plates are entirely concealed. Every block is securely held to the floor, and the finished surface of the blocks is in no way marred.

When thin blocks are used, it will be necessary to use quite thin fastening-plates, and in any case when the plates are not stiff enough it may be advisable to provide a bolster, (shown in Fig. 5,) which is inserted under the plate and preferably surrounds the screw. Such a bolster will support the plate and keep it from buckling.

It is clear that the use of this invention is not limited alone to the laying of parquet- 90 flooring. It can as well be made use of for securing paneling of any description whatever in place, and I do not wish to be limited to any extent beyond that made necessary by the state of the prior art.

I claim as my invention—

1. The combination with the blocks, said blocks having grooves in their edges thereby forming upper and lower ledges, the lower ledges at the corners being cut away, and the 100 grooves at these points lying parallel therewith, of a fastening-plate having inclined

sides received in the grooves and engaging the inclined portions thereof adjacent the corners of the blocks and being provided with projections extending into the grooves 5 formed in the sides of the blocks.

2. A fastening means for blocks in a device of the type set forth comprising an approximately rectangular plate formed with apertures and an outward projection at each

corner of said plate, said projections having to their outer ends pointed.

In testimony whereof I affix my signature in presence of two witnesses.

WILLIS S. KELSEY.
